Attorney

UNITED STATES PATENT OFFICE.

JOSEPH T. GOMEZ, OF GOLDFIELD, NEVADA.

SPARK-PLUG CLEANER.

1,391,471.

Specification of Letters Patent. Patented Sept. 20, 1921.

Application filed July 27, 1920. Serial No. 399,350.

To all whom it may concern:

Be it known that I, JOSEPH T. GOMEZ, a citizen of the United States, residing at Goldfield, in the county of Esmeralda, and 5 State of Nevada, have invented certain new and useful Improvements in Spark-Plug Cleaners, of which the following is a specification.

In the operation of internal combustion engines it is well known that the spark-plugs become carbonized, resulting in a failure to function properly unless the impeding coating is removed. My invention relates to 10 a spark-plug-cleaner for removing this coating.

The spark-plug-cleaners at present in use are deficient in the following particulars:

- (1) No provision is made for the cleaning of a number of spark-plugs at the same 20 time;
- (2) No provision is made for the automatic agitation of the cleaning medium;
- (3) Simple means for facilitating the 25 draining of the cleaning fluid after contamination with impurities are lacking.

My invention has as its object the provision of a spark-plug-cleaner of simple structure whereby the above-enumerated deficiencies are eliminated.

30 For a clear understanding of my invention, reference is made to the accompanying drawings in which—

Figure 1 is a perspective view of the spark plug cleaner;

35 Fig. 2 is a section on line 2—2 of Fig. 3, and

Fig. 3 is a section on line 3—3 of Fig. 2.

Referring to the drawings the receptacle 1, preferably made of metal, has an intermediate floor 2, containing a plurality of apertures 3, the walls of which are threaded and thereby adapted to receive spark-plugs 4.

The bottom 5 of the receptacle 1 is inclined slightly, to provide means for maintaining the lower surface of the cleaning medium at an angle to the horizontal to facilitate the draining of the cleaning medium 6, after contamination with impurities, 50 through the valve 7.

The cover 8, serving to prevent an excess of impurities when the device is in use, is hinged at 9 and 10, respectively, and securely locked by the spring members 11 and 12. The wall 17 of the receptacle is

provided with ears 13, 14, 15 and 16, admitting of a quick, easy and convenient attachment to an automobile body, the continuous periodic motion of the automobile, when in operation, serving as an agitating means for the cleaning fluid, thereby resulting in a more thorough cleaning of the spark-plug and its electrode than is obtainable by the devices at present in use.

The cleaner is adapted to perform the cleaning operation quickly, conveniently and effectively and is advantageous in that a number of spark-plugs may be cleaned simultaneously and the cleaning fluid may be easily drained after its contamination with impurities.

I claim:

1. A spark-plug cleaner comprising a receptacle provided with a plurality of apertures adapted to receive spark plugs, means for maintaining the lower surface of the cleaning medium at an angle to the horizontal to facilitate the draining of the cleaning medium and means for draining the receptacle.

2. A spark-plug-cleaner comprising a receptacle having an intermediate floor containing a plurality of apertures adapted to receive spark plugs, means for maintaining the lower surface of the cleaning medium at an angle to the horizontal to facilitate the draining of the cleaning medium and means for draining the receptacle.

3. A spark-plug-cleaner comprising a receptacle having an intermediate floor containing a plurality of apertures adapted to receive spark plugs, an inclined bottom to facilitate the draining of the cleaning medium, and means for draining the receptacle.

4. A spark-plug-cleaner comprising a closed receptacle having an intermediate floor containing a plurality of apertures adapted to receive spark plugs, an inclined bottom to facilitate the draining of the cleaning medium, and means for draining the receptacle.

5. A spark-plug-cleaner comprising a receptacle having an intermediate floor containing a plurality of apertures adapted to receive spark plugs, a spring-controlled cover, an inclined bottom to facilitate the draining of the cleaning medium, means for draining the receptacle and ears secured to the wall of the receptacle adapted to permit the attachment of the same to an auto-

mobile body, whereby the cleaning medium present in the receptacle is agitated on movement of the automobile.

6. A spark-plug-cleaner comprising a receptacle having a plurality of apertures adapted to receive spark-plugs, means for facilitating the draining of the cleaning fluid, means for draining the receptacle and means secured to the wall of the receptacle adapted to permit the attachment of the same to an automobile body; whereby the cleaning medium present in the receptacle is agitated on movement of the automobile.

7. A spark-plug-cleaner comprising a receptacle having an intermediate floor containing a plurality of apertures adapted to receive spark-plugs, means for facilitating the draining of the cleaning fluid, means for draining the receptacle, and means secured to the wall of the receptacle adapted to permit the attachment of the same to an automobile body, whereby the cleaning medium present in the receptacle is agitated on movement of the automobile.

In testimony whereof I affix my signature. 25
JOSEPH T. GOMEZ.
